DEVELOPMENT AND LAYOUT INSTRUMENT

Gerald J. Henjum, Hollywood, Calif., assignor of
one-third to Albert H. Farness, North Holly-
wood, and one-third to Chester H. Sherer, Los
Angeles, Calif.

Application May 22, 1945, Serial No. 595,109

4 Claims. (Cl. 33—104)

1

This invention relates to a new and improved drafting instrument for developing flat patterns of the intersection of surfaces of revolution such as pipes used for fluids, and standards or mountings wherein it is desired to develop a wrap-around template or pattern to facilitate the cutting of the end of a pipe, as when it is desired to attach a branch pipe to another pipe at any angle thereto.

By well known mechanical drafting processes, familiar to engineering draftsmen, it is possible to develop such intersections and patterns or templates on the drawing board, with the use of conventional drafting instruments. Such processes are responsible for considerable delay in field and shop work, where the welder or sheet metal worker desires to do the job on the spot. It is, therefore, an object of this invention to provide a layout instrument capable of use by a mechanic for developing such intersections as needed, at a great saving of time as compared to conventional mechanical drawing procedures. The use of my herein described instrument eliminates the need of computations and the use of conventional drafting instruments, as I provide a series of scales for each standard pipe size to enable the workman to complete the development or layout of a wrap-around pattern or template, which can be applied directly to the end of the pipe to be cut or beveled to fit against another pipe at the angle and/or offset contemplated. It is also sometimes convenient to develop a wrap-around template to transfer the outline of the hole to be cut in the pipe to which the branch is to be applied, and this can readily be done with the instrument of my invention.

With these and other objects in view, as will more fully appear as the description proceeds, my invention consists in the construction, novel features and combination of scales hereinafter more fully described, pointed out in the claims appended, and illustrated in the accompanying drawing wherein:

Figure 1 is a view of one side of a triangle embodying the features of this invention; and,

Figure 2 is a view of the other side thereof.

While I have chosen to illustrate my invention as incorporated in a triangle similar in outline to a conventional draftsman's triangle, it is to be understood that the exact proportions and/or shape of the instrument is immaterial to the principles of my invention, since my coordinated series of scales can be applied to other configurations without affecting the usefulness thereof.

2

The practical embodiment chosen for illustration comprises a draftsman's triangle 10 of conventional outline, having the usual central opening 11 whereby the inner edges of the side portions 12, 13 and 14 are parallel to the external edges. In addition, I have shown a protractor arc 15 having suitable indicia, this feature being useful in setting out the desired angles at which the pipes are to be joined.

The coordinated series of scales as shown and hereinbefore referred to, are grouped in various standard pipe sizes, which as is well known, are rated as the nominal inside diameters, varying in this case from one and one-quarter inches to eight inches. In each standard size, I show a scale 16 marked ID (inside diameter) which represents the successive projections on a diameter of arcs of twenty-two and one-half degrees, i. e., a semi-circle is divided into eight equal parts, and the projections of these points on the diameter form the scale. For convenience I show only four points plus the center line 17 for a ninety degree arc, as the other four points can be obtained by reversing the triangle and scale. A second scale 18, marked OD (outside diameter) covers four points running the other way from the center line 17, and corresponds to the actual outside diameter of standard pipe of the nominal inside diameter specified. In order to develop a flat pattern of the circumference of a pipe of given nominal size, I provide a third scale 19, marked X, which gives the actual developed length of the arcuate segments divided as in producing the OD scale 18.

In order to be able to strike arcs corresponding to the actual outside diameters of the several nominal pipe sizes, I provide a series of perforations 20, one of which is marked as the center O, and the others positioned at the corresponding radii and marked for the nominal pipe sizes.

In the use of my layout instrument, the usual mechanical drafting procedure is materially shortened. In the simplest case of a right angled joint between equal sized pipes, it is only necessary to draw two lines at forty-five degrees and to carry the projections of the OD and ID scales normal to one line to their intersection with the other lines, and measure their length on the forty-five degree line, transferring these lengths to ordinates erected at intervals determined by the X scale to develop the layout or wrap-around template for cutting the ends of the pipe.

In a more complicated case of unequal pipe sizes, when the branch may be both offset and at

a specified angle to the main run of pipe, the procedure is a trifle more complicated, but still basically straightforward and readily apparent to those skilled in the art. In order to determine the ordinates to be applied to the layout or wrap-around template lines determined by the X scale for the branch pipe line, it is necessary to draw a base line and strike an arc of the OD of the main run tangent thereto. The amount of offset is marked from the point of tangency and the ID and OD scales centered on the offset, the scale markings being carried down to the arc previously marked, and then carried out parallel to the base line. The branch pipe center line is drawn at the desired angle and the ID and OD scales marked normal thereto, being carried down parallel to the center line of the branch pipe to intersect the corresponding lines parallel to the base line first drawn. The lengths of the lines parallel to the center line of the branch pipe form the ordinates of the developed or wrap-around template.

I find it desirable to use the ID scales for the "open" sides of the branch pipe, and the OD scales for the "closed" sides of the pipes, since by so doing the necessity of beveling the cut ends of the pipe is avoided, and in addition, a V is left for the welding material, in the case of standard pipe which has appreciable wall thickness. If working with thin-walled tubing or sheet metal, such as stove pipe, the outside diameter is also practically the nominal pipe size, and both ninety degree arcs can be laid out from the ID scales by reversing the triangle about the center line of the scale. However, the illustrated embodiment of the developed length scale 19 allows for appreciable pipe thickness, so that for thin metal the spacings of the flat pattern should be reduced in proportion to the difference between the circumference of standard pipe and the desired circumference of the tubing, by setting the scale at an angle to the base line sufficient to reduce the spacings the required amount.

In the use of the instrument of my invention, the development or wrap-around template may be drawn on any convenient material. If only a single joint is to be made, it may be drawn on paper, which is subsequently wrapped around the pipe and the outline transferred thereto as by prick punching. If a number of duplicate joints are to be made, the template may be drawn on

flexible sheet metal either for transfer direct to the pipe, or as a template for contouring a collar to serve as a guide for cutting the ends of a number of pipes to the same pattern.

Obviously, my invention is susceptible of embodiment in forms other than that chosen for illustration herein, and applicable to other and analogous uses than pipe welding and/or assembling, and I therefore do not desire to be limited other than by the permissible scope of the claims appended hereto.

I claim:

1. A layout instrument embodying a polygonal sheet material having a plurality of scales disposed along the edges thereof, comprising base line projections of equally divided circular arcs corresponding to the inside and outside diameters of a plurality of standard pipe sizes, together with scales of the developed circumference of similar pipe sizes divided into units corresponding to the spacings of said circular arcs.

2. An instrument adapted to develop the intersections of surfaces of revolution, embodying a member having at least one straight edge, a series of coextensive indicia for at least one circle of a desired diameter marked on said straight edge, comprising a scale of base line projections of uniform divisions of an arc of said circle, and a second scale of the developed lengths of said arcuate divisions.

3. A drafting instrument comprising a plane figure having a plurality of straight edges, and coordinated series of scales marked thereon for a plurality of standard pipe sizes, each set of scales for a particular pipe size including scales of projections of equal arcuate divisions of circles corresponding to the inside and outside diameters of the particular pipe size, and a scale of the developed length of the arcuate divisions of the outside diameter of said pipe size.

4. A layout instrument comprising a triangle having self-contained means for developing the intersection of surfaces of revolution, said means comprising a plurality of scales of base line projections of a plurality of arcuate curves of various radii divided into equal segments, and corresponding scales of the developed length of such arcuate segments for each radius of said first mentioned scales.

GERALD J. HENJUM.
